DESIGN FOR A SEPARABLE PIN OR THE LIKE

John Rubel, New York, N. Y.

Application October 9, 1943, Serial No. 111,313

Term of patent 3½ years

To all whom it may concern:

Be it known that I, John Rubel, a citizen of the Republic of France who has declared his intentions of becoming a citizen of the United States, residing in New York city, in the county of New York and State of New York, has invented a new, original, and ornamental Design for a Separable Pin or the like, of which the following is a specification, reference being had to the accompanying drawing, forming part thereof.

Fig. 1 is a plan view of a separable pin or similar article showing my design.

Fig. 2 is an elevational edge view of the separable pin shown in Fig. 1.

Fig. 3 is an enlarged fragmentary view of the chain portion.

Fig. 4 is a plan view of the larger pin shown in Fig. 1, in separated position.

I claim:

The ornamental design for a separable pin or similar article, substantially as shown.

JOHN RUBEL.
